UNITED STATES PATENT OFFICE.

AARON KETO, OF FITCHBURG, MASSACHUSETTS.

WASHING-MACHINE.

1,104,904.

Specification of Letters Patent.

Patented July 28, 1914.

Application filed April 1, 1914. Serial No. 828,705.

To all whom it may concern:

Be it known that I, AARON KETO, a citizen of Finland, residing at Fitchburg, in the county of Worcester and State of Massachusetts, have invented certain new and useful Improvements in Washing-Machines, of which the following is a specification.

This invention relates to improvements in washing machines and more particularly to devices of this class that can also be used as churning or for similar purposes where agitation of a liquid by means of a rotary drum is desired.

My invention contemplates an outer rotary drum and an inner rotary drum carried thereby, the walls of the inner rotary drum being reversible to prevent contamination of the contents of the inner drum by any residue from matter previously contained therein.

With the foregoing and other objects in view the invention consists in the combination and arrangement of parts to be herein-after fully described in the following specification, pointed out in the claims and illustrated in the accompanying drawings which form a part of said specification and in which:

Figure 1 is a front elevation of my improved washing machine. Fig. 2 is a section taken on line 2—2 of Fig. 1. Fig. 3 is an end elevation of the device with a portion of the outer drum and the inner drum shown in section. Fig. 4 is a section taken on line 4—4 of Fig. 1. Fig. 5 is a section taken on line 5—5 of Fig. 1.

Like reference characters indicate corresponding parts throughout the several views.

My machine comprises a frame 1 provided with feet 2 and in said frame trunnions 3, 3 are journaled which carry the outer drum 4 and one of which is provided with an operating handle 5. The outer drum, which is preferably square in cross section, is provided upon each corner with two threaded castings 6, 6 through which the threaded stem 7 of a hand wheel 8 extends and which stem upon its inner extremity carries a clamp 9 adapted to grip one corner of the inner drum 10, also square in cross section. Two opposite sides of the drum 10 are pro-

vided with marginal pins 11 which extend through said sides and upon which the remaining sides of the drum obtain a bearing; 55 the four sides of the drum being so fitted together as to be water tight. The construction of the inner drum is such that its walls can be individually removed and inverted so that when the machine has been used as a 60 washing machine the several walls can be inverted to permit its use as a churn. The outer drum is provided with a hand-controlled clamping member 12 which extends through its wall and is provided with a head 65 13 adapted for frictional engagement with the inner drum to further secure the same in adjusted position with relation to the outer drum. The outer drum, moreover, is provided with a sliding wall B which serves as 70 a cover and access to the interior of the inner drum is to be had by removing one of its four walls. A drain pipe 14 serves to withdraw the contents of the machine when desired.

What is claimed is:

1. In a washing machine, an outer rotary drum, square in cross section, mounted in a frame and provided with an operating handle, an inner rotary drum, square in 80 cross section, formed with reversible walls, clamping means releasably securing said drums together and a drain pipe for said inner drum.

2. In a washing machine, an outer rotary 85 drum, square in cross section, mounted in a frame and provided with an operating handle, an inner rotary drum, square in cross section, formed with removable walls, marginal pins carried by one pair of opposite walls as bearings for the remaining pair of walls, clamping means for releasably securing said walls in operative relation and for releasably securing said drums together and a drain pipe for said inner drum. 90 95

In testimony that I claim the foregoing as my own I have hereto affixed my signature in the presence of two subscribing witnesses.

AARON KETO.
